UNITED STATES PATENT OFFICE.

ROBERT McC. JOHNSTONE, OF ROSELLE PARK, NEW JERSEY, ASSIGNOR TO CAMERON MACHINE COMPANY, OF BROOKLYN, NEW YORK, A CORPORATION OF NEW YORK.

WINDING MECHANISM.

Application filed November 11, 1920. Serial No. 423,227.

To all whom it may concern:

Be it known that I, ROBERT McC. JOHNSTONE, a citizen of the United States, and a resident of Roselle Park, in the county of Union and State of New Jersey, have invented certain new and useful Improvements in Winding Mechanism, of which the following is a specification.

This invention relates generally to winding mechanism, and has more particularly reference to means for controlling a roller such as the top pressure roller forming part of the surface rewinding means in a slitting and rewinding machine.

In devices of this character, it has heretofore been customary to provide pinions on the framework and to mount racks for engagement therewith on a vertically movable carriage carrying the top pressure roller.

When it was desired to manually lift or lower the carriage mounting the top pressure roller, rotation of the pinions in the proper direction would effect the desired result. It is not, however, always desirable to lift and lower heavy racks, if for no other reason than because, in the arrangement heretofore employed, it is difficult to maintain a given weight to the top pressure roller throughout the winding operation with the result that coils of material are wound under different degrees of pressure at different times during the rewinding operation. A reversal of the usual arrangement is therefore desirable at times. It will be understood, however, that if the racks are stationary on the frames and if the pinions are mounted on the movable carriage, the rise and fall of said carriage will move any operating handle that may be attached to the pinions up or down. This is inconvenient

for the operator because at times the handle may be so high up as to be not readily accessible and also because the operator prefers to have a definite and unchanged position for an operating handle so that he may instinctively, as it were, reach out for the right place. In addition, the operating handle would change its position vertically during operation which would tend to confuse the operator.

The main object and feature of the invention is to so arrange an operating handle for actuating pinions on a movable carriage that it will always occupy substantially the same

position, regardless of the vertical position of the pinions and carriage, and it consists of the features of construction, combination of parts and arrangement of elements hereinafter described, a preferred form of which is disclosed in the accompanying drawings, 60 in which—

Fig. 1 is a front elevation, partly broken away, of a winding machine embodying the invention.

Fig. 2 is a side elevation of the parts shown in Fig. 1.

Fig. 3 is a sectional view on the plane of line 3—3 of Fig. 2.

Fig. 4 is a sectional view on the plane of line 4—4 of Fig. 2.

The form of winding mechanism herein disclosed consists of front and rear rewinding drums 1 and 2, a rewind shaft 3 and a top pressure roller 4. It will be understood that the rewind shaft is displaced upwardly 75 as the rewound material accumulates and is to that effect provided with reduced portions 5 that extend into slots in sliding member 6. Top pressure roller 4 is likewise displaceable vertically by the rise of the re- 80 wound material and is mounted in a carriage 7 sliding on the vertical guides 8. Sliding members 6 are carried by carriage 7 and slide in guide members 9 on the framework. Carriage 7 is provided with tie rod 10 and 85 pinion shaft 11 extending transversely of the machine and has extensions 12 that engage the rear face of guides 8. 13 indicate pinions mounted on the pinion shaft to engage upright racks 14 on the front face of 90 guides 8. It is customary to drive the top pressure roller and this is accomplished, in the present instance, by means of slip friction drive member 15 imparting rotation to splined shaft 16 and bevel gears 17. The 95 amount of pressure of the top pressure roller is regulated by weights 18 carried by flexible connections 19 that pass over sheaves 20 and are attached to the vertically movable carriage. Mounted on pinion shaft 11 is a 100 spiral gear 21 and meshing with it is another spiral gear 22 carried by telescoping shaft 23 arranged at right angles to shaft 11. Said telescoping shaft is pivotally supported on the framework at 24 and also pivotally supported by means of bearing 25 loosely surrounding pinion shaft 11. It will 105 be understood that as the diameter of the re-

wound material increases, carriage 7 is moved upward, gears 22 and 23 remaining in mesh and the telescoping shaft lengthening and swinging around its pivots. This will cause 5 rotation of telescoping shaft in one direction and pawl 26 will click over ratchet 27. When the rewound material is removed from the machine, backward rotation of shaft 23 and lowering of carriage 7 will be prevented 10 by the ratchet and pawl. When it is desired to lower carriage 7 manually, pawl 26 may be disengaged from ratchet 27 and shaft 23 may then be turned to lower carriage 7 either by actuating handwheel 28 or 15 by gravity. So likewise carriage 7 may be raised manually by turning handwheel 28.

Pawl 26 is pivoted at 29 and spring 30 normally urges it into engagement with ratchet 27. The action of the spring may 20 be overcome by manipulating handle 31.

To prevent binding of the parts and to facilitate smoothness of action, the telescoping shaft is constructed as follows: The inner shaft member is provided with grooves 32 and the outer sleeve member is provided with rotatable rollers 33 that travel in grooves 32 of the inner shaft. If desired a similar means may be used between shaft 16 and bevel gear 17.

30 I claim:

1. In winding mechanism, upright guides, a carriage vertically movable on said guides, upright racks on said guides, a transversely extending pinion shaft on said carriage, pinions on said shaft to engage the racks, a telescoping actuating shaft at right angles to the pinion shaft, transmission means between the two shafts, and means for sup-

porting the actuating shaft on the framework and on the movable carriage. 40

2. In winding mechanism, upright guides, a carriage vertically movable on said guides, upright racks on said guides, a transversely extending pinion shaft on said carriage, pinions on said shaft to engage the racks, a 45 telescoping actuating shaft at right angles to the pinion shaft, transmission means between the two shafts, means for supporting the actuating shaft on the framework and on the movable carriage, and a ratchet and 50 pawl mechanism to admit of rotation of the telescoping shaft in one direction and to prevent its rotation in the other direction.

3. In winding mechanism, upright guides, a carriage vertically movable on said guides, 55 upright racks on said guides, a transversely extending pinion shaft on said carriage, pinions on said shaft to engage the racks, a telescoping actuating shaft at right angles 60 to the pinion shaft, transmission means between the two shafts and means for pivotally supporting the actuating shaft on the framework and on the movable carriage.

4. In a winding mechanism, a vertically movable carriage, a shaft carried thereby, a 65 two part telescoping shaft at right angles to the first shaft, rollers carried by the outer member of the telescoping shaft engaging slidingly with the inner member of the telescoping shaft and rotating therewith, and 70 inter-meshing gears on the two shafts.

Signed at New York city in the borough of Brooklyn, in the county of Kings, and State of New York, this 3 day of November 1920.

ROBERT McC. JOHNSTONE.
